Primary Examiner—Peter M. Cuomo*Assistant Examiner*—James O. Hansen**[57] ABSTRACT**

A detachable wardrobe comprises a frame device and a casing enclosing the frame device. The frame device comprises a top frame having four three-way corner joints, a middle frame having four four-way joints, a bottom frame having four three-way bottom joints, a first bearing plate disposed on the bottom frame, a second bearing plate disposed on the middle frame, and a plurality of longitudinal rods disposed between the top frame and the middle frame and disposed between the middle frame and the bottom frame.

FIG. 2

F I G. 3

F I G. 4

1 DETACHABLE WARDROBE

BACKGROUND OF THE INVENTION

The present invention relates to a wardrobe, and more particularly, the present invention relates to a detachable wardrobe.

Most conventional wardrobes cannot be detached at all. The wardrobe has a single chamber only. It is difficult to provide a detachable wardrobe with three chambers.

SUMMARY OF THE INVENTION

An object of the present invention is to provide a detachable wardrobe which can be easily detachable or assembled.

Accordingly, a detachable wardrobe comprises a top frame having four three-way corner joints, a middle frame having four four-way joints, a bottom frame having four three-way bottom joints, a first bearing plate disposed on the bottom frame, a second bearing plate disposed on the middle frame, and a plurality of longitudinal rods disposed between the top frame and the middle frame and disposed between the middle frame and the bottom frame. The top frame has a plurality of hanger rods. The middle frame has a plurality of crossbars. The bottom frame has a plurality of transverse bars. The casing encloses the frame device. The casing has an upper housing enclosing the top frame, a lower housing enclosing the middle frame, and a middle housing disposed under the upper housing. An upper chamber is formed between the upper housing and the middle housing. A middle chamber is formed between the middle housing and the lower housing. A lower chamber is formed between the lower housing and the first bearing plate.

BRIEF DESCRIPTION OF THE DRAWINGS

FIG. 1 is a perspective assembly view of a detachable wardrobe of a preferred embodiment in accordance with the present invention;

FIG. 2 is a perspective schematic view illustrating an application of a detachable wardrobe;

FIG. 3 is a perspective assembly view of a frame device of a detachable wardrobe of a preferred embodiment in accordance with the present invention; and

FIG. 4 is a perspective assembly view of a casing of a detachable wardrobe of a preferred embodiment in accordance with the present invention.

DETAILED DESCRIPTION OF THE INVENTION

Referring to FIGS. 1 to 4, a detachable wardrobe comprises a frame device 32 and a casing 31. The frame device 32 comprises a top frame 321 having four three-way corner joints 325, a middle frame 324 having four four-way joints 327, a bottom frame 325 having four three-way bottom joints 328, a first bearing plate 4b disposed on the bottom frame 325, a second bearing plate 4a disposed on the middle frame 324, and a plurality of longitudinal rods 322 disposed between the top frame 321 and the middle frame 324 and disposed between the middle frame 324 and the bottom frame 325.

2

The top frame 321 has a plurality of hanger rods 329. The middle frame 324 has a plurality of crossbars 320a. The bottom frame 325 has a plurality of transverse bars 320b. Each bottom joint 328 is connected to a foot 3281.

5 The casing 31 encloses the frame device 32. The casing 31 has an upper housing 315a enclosing the top frame 321, a lower housing 315a enclosing the middle frame 324, and a middle housing 315a disposed under the upper housing 315a. An upper chamber A is formed between the upper housing 315a and the middle housing 315b. A middle chamber B is formed between the middle housing 315b and the lower housing 315c. A lower chamber C is formed between the lower housing 315c and the first bearing plate 4b.

15 A first fabric 311 covers the upper chamber A. A second fabric 312 covers the middle chamber B. A third fabric 313 covers the lower chamber C. A first zipper 314a fastens the first fabric 311 on the casing 31. A second zipper 314b fastens the second fabric 312 on the casing 31. A third zipper 314c fastens the third fabric 313 on the casing 31.

20 The present invention is not limited to the above-mentioned embodiment but various modification thereof may be made. Furthermore, various changes in form and detail may be made without departing from the scope of the present invention.

I claim:

1. A detachable wardrobe comprises:

a frame device,

a casing enclosing the frame device,

the frame device comprising a top frame having four three-way corner joints, a middle frame having four four-way joints, a bottom frame having four three-way bottom joints, a first bearing plate disposed on the bottom frame, a second bearing plate disposed on the middle frame, and a plurality of longitudinal rods disposed between the top frame and the middle frame and disposed between the middle frame and the bottom frame,

35 the top frame having a plurality of hanger rods,

the middle frame having a plurality of crossbars,

the bottom frame having a plurality of transverse bars,

the casing having an upper housing enclosing the top frame, a lower housing enclosing the middle frame, and a middle housing disposed under the upper housing,

40 an upper chamber formed between the upper housing and the middle housing,

a middle chamber formed between the middle housing and the lower housing, and

45 a lower chamber formed between the lower housing and the first bearing plate.

2. A detachable wardrobe as claimed in claim 1, wherein 50 a first fabric covers the upper chamber.

3. A detachable wardrobe as claimed in claim 1, wherein 55 a second fabric covers the middle chamber.

4. A detachable wardrobe as claimed in claim 1, wherein 60 a third fabric covers the lower chamber.
